UNITED STATES PATENT OFFICE

ERICH H. LICHTENBERG, OF MILWAUKEE, WISCONSIN, ASSIGNOR TO KOEHRING COMPANY, OF MILWAUKEE, WISCONSIN, A CORPORATION OF WISCONSIN

WORM-DRIVE CRANE

Application filed June 25, 1928. Serial No. 288,159.

This invention has to do with the art of excavating and material handling machines, and embodies novel improvements in the type of such machines commonly called rotary cranes, wherein there are provided three general features of construction, namely, a suitable traction base, a crane or turn-table body mounted upon said base, and a boom and bucket excavating apparatus associated with the body for operation by machinery thereon.

This invention appertains directly to the machinery carried by the body of the crane, and comprising drum operating mechanism suitably motor driven, by which the boom and bucket actions of the machine are controlled.

Heretofore, the machinery upon a crane body has been unduly complicated including certain cable operating drums and extensive trains of gearing for the transmission of power to the drums from the motor, and for conveying the power to the traction mechanism by which the machine is propelled.

My invention intends to produce an improved operating drum unit for a crane, wherein the necessity for using the side frames and extensive gearing such as employed today is obviated, though it is within the purview of my invention to employ the side frames if for some special reason they should be necessary.

By dispensing with side frames and extensive trains of gearing, I am enabled to produce my boom and bucket operating mechanism at a greatly lowered cost, simplify the controls materially and otherwise generally cheapen the cost of production of the type of large machines to which my invention particularly relates.

In the carrying out of my invention, I utilize a worm gear unit which I think is wholly novel in its adaptation to the particular use to which I put it. The said worm gear unit is associated in a novel manner with the drum features that are required for the operation of the boom and excavating devices of cranes of those types known as clam shell, dragline and shovel cranes. Moreover, in the construction of my drum operating worm gear mechanism, I utilize a very

simple arrangement of drums, relatively few actuated spur gears, and very advantageous driving connections between the unit and the traction operating means at the base of the crane.

Obviously, if I am able to do away with a large number of the ordinary gears required in crane operating machinery of the type of my invention and eliminate the employment of side frames and other parts which require the use of considerable precision machining work, the desired results hereinbefore outlined will be accomplished.

By the employment of the special type of worm gear unit which I have referred to as the operating means for the drum mechanism and also the traction features, I am enabled to arrange the power unit or engine, usually a gas motor longitudinally of the cab or crane body.

This, in addition to the economy of space afforded by the said unit itself, enables all of the machinery in the car body to be assembled in a rather narrow compass, permits the cab or swing body to be constructed, narrower than heretofore, if desired, and if the said body is built as wide as heretofore, allows a great deal of space therein from which to enable access to the machinery in the handling of the crane.

In the accompanying drawings, I illustrate a preferred form of machine embodying my invention, and the figures of the drawings may be briefly described as follows:—

Figure 1 is a side elevation of a crane showing the invention applied thereto.

Figure 2 is a view showing more particularly the crane body and traction base, and bringing out the arrangement of the drum operating mechanism, driving connections leading to the traction or caterpillar driven parts, certain parts being broken away.

Figure 3 is a top plan view of the machine looking down on the swing or crane body and illustrating to some extent the simple form of the worm gear unit.

Figure 4 is a vertical sectional view taken about on the line 4—4 of Figure 2.

Figure 5 is an enlarged view showing the main worm gear housing unit, parts broken

away to illustrate the manner of entering the engine shaft into the said unit, and mounting thereon of the driven worm.

Figure 6 is a front view of the parts shown in Figure 5 particularly, the upper part of the worm gear housing being shown in section.

Figure 7 is a fragmentary sectional view bringing out more clearly the mounting and arrangement of the umbrella gear forming a part of the gear train for forming the traction base and for causing swinging of the swing body.

Figure 8 illustrates the brake means to be applied to stop swing of the body on the traction means, and

Figure 9 is a perspective view of a bevel cupped gear partly in section, which cooperates with the traction and swing mechanism.

I now describe the general crane construction illustrated in Figure 1 as comprising the swing body A, the traction base B, the shovel boom C, dipper handle D and dipper E. Excepting for the operating drum mechanism and arrangement of the power plant and traction driving connections, my crane embodies dipper operating, crowding and racking in cable means 1; also dipper hoisting cable means 2; and also cable raising means 3 for the boom C substantially like the corresponding features of Russell Letters Patent No. 1,639,752, issued August 23rd, 1927, and Russell Letters Patent No. 1,662,902, issued March 20th, 1928. I do not think it necessary therefore to refer to these particular features of my crane, as regards the boom and excavating devices since they may be very considerably modified within the purview of the invention and the construction illustrated is merely to exemplify the adaptation of my particular improvements. Moreover, of course, instead of the boom C and excavator D type of attachment shown in Figure 1, there may be substituted a suitable clam shell boom and clam shell bucket cable apparatus, or there may be used what is known as the dragline type of boom and bucket apparatus, these all being interchangeable, after a manner now known to those versed in the art.

I refer particularly now therefore to the features comprising my invention and to Figures 2 and 4 of the drawings especially. In Figure 2 it will be observed that the power unit which is a gasoline motor 4 is disposed longitudinally at the rear central portion of the crane body A and the said power unit has its power shaft extending forwardly and suitably connected with the driving shaft 5 of my worm gear driving unit or mechanism.

There may be interposed between the engine 4 and the shaft 5, suitable clutch mechanism in the clutch housing 6, but same is not illustrated as not material to the invention.

The worm gearing of my invention is ar-

ranged within a gear housing 7, see Figure 4, having at its left and right sides, the outstanding journals 8 and 9 that perform a dual function as they constitute bearings in which are mounted the drum drive shaft 10, and also constitute supporting journal bearings upon which are disposed for rotation the drum 11 at the left and the drum 12 at the right. The journal 9 is carried by a removable side plate 13 forming a part of the right side of the housing 7. This plate 13 is removable and slightly cupped or recessed at the central portion of its outer surface to receive the inner flange of the drum 12. Similarly the housing 7 at its left side is recessed or cupped to receive the inner flange of the drum 11. The provision of the cover or side plate 13 of the housing 7 enables access to the interior of the housing in the upper portion of which is mounted the driving worm gear 16 keyed to the shaft 10. The drums 11 and 12 are thus afforded a loose mounting upon their trunion or journal members 8 and 9. The drums 11 and 12 are equipped with outwardly projecting brake and clutch drum flanges designated 11^a and 12^a, clutch means being provided to cooperate for connecting the parts 11^a and 12^a with the shaft 10 to rotate therewith, at will. The braking means is employed of course, to hold the drums stationary, when the cable means wound around said drums requires such operation, in the usual well known manner.

When the worm gear unit now being described, is employed for a shovel crane, the drum 11 will be reversibly operable, and will have the cable means to wind thereabout, so that crowding and racking in operations of the dipper E may be performed. Under such conditions, the drum 12 will be used to operate the cable means for hoisting the dipper E.

When my machine is used for clam shell purposes one of said drums will be employed for the hoisting line of the clam shell and the other for the closing line, but the reversible operation of the drum 11 is not necessary to be employed.

Again, when my machine is used for dragline purposes, one of the said drums 11 and 12, will be employed for the hoisting line of the drag bucket, and the other will be employed for the dragline also; similarly, to the clam shell operation, under such conditions, no reversal of operation of the drum 11 will be necessary as the same is only employed for power shovel purposes. The worm gear 16 is the main drum mechanism operating gear and is directly engaged with the worm 17 on the driving shaft 5 operated from the engine shaft under suitable control. Below the worm 17 is disposed a secondary worm gear mechanism comprising the worm gear 18 adapted to function under some conditions as a driving means for causing the reverse operation of the drum 11 in a shovel crane;

when the cranes to which my invention is applied are dragline and clam shell cranes, the worm gear 18 functions primarily only for operating the traction mechanism and for controlling the swing of the crane body which 5 is its purpose for all cranes.

The worm gear 18 is mounted in the lower portion of the housing 7 which lower portion is provided with offstanding hollow journals 19 and 19^a, the journal 19^a similar to the 10 formation of the upper portion of the casing being carried by a side or cover plate 21 removable from the main housing 7 to enable access to the interior of said housing at its 15 lower portion. A traction and swing shaft 20 is mounted in the lower portion of the housing 7 supported by the journals 19 and 19^a as bearings therefor, and the worm gear 18 is keyed to this shaft. The worm gears 16 and 18 are therefore driven in opposite directions. 20

At its lower end portion, the gear housing 7 is formed with outwardly projecting arms 7^a and 7^b provided with bearings for the shaft 22 and said shaft 22 therefore constitutes an anchoring means connecting the 25 housing 7 with the vertical short standards 23 of the base casting.

At its central lower extreme portion, the housing 7 is formed with a recess providing 30 a bearing 26 for the upper trunnion 27 of the cupped bevel-gear 28, seen best in Figures 4 and 9. This cupped bevel-gear is equipped with a downwardly projecting or lower trunnion 29 which is received in a bearing 30 in the central lowest portion of the base casting 24.

It will be understood, of course, that anti-friction rollers or other bearings may be provided in the bearing cavities or parts 26 and 30 in accordance with the best provisions of 40 machine designing, but these are not material to the invention and such bearings will not again be referred to.

The function of the worm gear 18 as a reversing drive means for the drum 11, will now 45 be set forth. On the shaft 20 is keyed a pinion 31 alongside the worm gear 18 and meshing with a similar pinion 32 above it and carried by the counter shaft 33, see Figure 4. The counter shaft 33 is supported in a hollow 50 journal member 34 offstanding from the left of the housing 7 about centrally between its upper and lower ends, and carries a driven gear 35 which meshes in turn with a larger gear 36 carried by the drum 11 in any suitable 55 manner. The gear 35 is indirectly supported by the shaft 33, and is shiftable slightly from its full line position of Figure 4 to its dotted line position of said figure. In the latter position the gear 35 may enter and directly interlock with a toothed gear recess of the boom hoist drum 37 about which may wind the cable 37', see Figure 1, by which the boom 60 C may be raised or lowered and held in desired adjusted positions within the range of 65

such movement. The drum 37 is journaled upon the hollow journal member or trunnion 34 in which the shaft 33 is mounted. I have not illustrated any shifting means for the gear 35 but various kinds of such means may 70 be resorted to. For instance, the gear may have a grooved hub and a shift lever or rod may be engaged by a shifting yoke with said hub to thereby enable movement of the gear inwards or outwards in relation to the 75 drum 37.

Obviously, by reason of the train of gears and pinions 31, 32, 35 and 36, the drum 11 may be driven in a direction reversely to that in which it will be driven when the clutch 80 means coacting with the clutch and brake drum 11^a are used to connect said drum 11 with the shaft 10. On the shaft 33 is arranged a clutch and brake drum 33^a having a hub portion keyed to the shaft 33 and on 85 which the gear 35 is splined to shift in the manner above stated. The use of the clutch means associated with the drum 33^a may, of course, enable the gear 35 to be connected with the shaft 33 and driven thereby or not, 90 as may be desired. Brake means cooperating with the drum 33^a will enable the holding of the boom hoist cable 37' at any adjustment of the boom desired when the gear 35 is in co-operation with the drum 37. 95

The portion of the housing 7 opposite the drum 37 is in the form of a cover or side plate removably applied to the body of the housing and through which access may be had to the interior of the housing from the left side 100 thereof as viewed in Figure 4.

Passing now to the function of the worm gear 18 in its cooperation with the traction features, and the swing gear features of my invention, I note, as will be seen in Figures 105 2 and 4, that the cupped bevel-gear 28 has its teeth engaging opposite bevel-gears 39 and 40 on the shaft 20. At the inner sides of these bevel-gears 39 and 40, are cap glands 41, the purpose of which is to prevent the escape 110 of lubricant received in the housing 7. In other words, the housing 7 will be supplied with a lubricant so that the gearing enclosed thereby will be free running in oil all the time, the cap glands 41 coacting to close the 115 outer ends of the journals or trunnion members 19 and 19^a.

Similarly, cap glands 14 and 15 are provided to coact with the outer ends of the journals 8 and 9 to retain lubricant in the housing 7. 120

Keyed to the gear supporting portion 28^a, see Figure 9 of the cupped bevel-gear 28, is a spur gear 42 which meshes as seen in Figure 2 with a swing and traction gear 43 suitably 125 mounted upon the base casting 24 of the body A. The gear 43 has two functions. In the first place, it is keyed or otherwise secured to the center pin shaft 44 which forms the connection between the crane body A and the 130

traction base B, and is adapted to drive said shaft and the bevel-gear 45 at the lower end thereof. Said bevel-gear 45 meshes with a similar gear 46, see Figure 4, on the traction shaft 47, and is therefore adapted to drive said traction shaft. The traction shaft 47 and the driving connections therebetween, and the endless traction members 48 form features of an invention other than my own and it suffices to state that there are employed combination clutch and brake sets 49 cooperative with the shaft 47 and connected with chain driving sprockets 50 having the sprocket chains 51 leading to the traction belt drive sprockets 52. Power may be transmitted from the shaft 47 through the combination clutch and brake sets 49 to the sprockets 50, and thereby to the traction belts 48 to drive either or both of these belts at will. Or again, either or both of the traction belts may be braked to hold either or both, more or less stationary, for controlling steering actions. When the brakes are applied to both of the clutch and brake sets 49, the gear 46 will become locked, and will lock the center pin shaft 44 and the umbrella gear 43 keyed thereto. Under these conditions, it will be apparent that if the swing and traction gear 42, see Figure 2, is operated in either direction by the cupped bevel-gear 28, the said gear 42 will travel around the gear 43 and swing the crane body in the customary well known manner along with its boom and excavating apparatus.

For the purpose just last described therefore, I provide on the shaft 20, the clutch drums 52^a for clutching either of the bevel-gears 39 and 40 to the shaft 20 driven by the worm gear 18 and depending upon which one of these bevel-gears is rendered operative, the cupped gear 28 will be operated in one of opposite directions and thereby correspondingly actuate the spur gear 42 which travels around the umbrella gear 43 when said umbrella gear is held stationary.

Of course, when the umbrella gear 43 is not held stationary, it is in fact, a traction drive gear when driven in either direction by the swing and traction gear 42 and there will be no turning of the body A of the crane.

When the gears 42 and 43 are employed for swinging the body of the crane, I must necessarily provide some means for stopping the swing movement when the boom C and excavating apparatus carried thereby have been swung to the desired position, supplying those for discharge or for digging. To this end, I provide, as seen in Figure 4 and the detail view of Figure 8, a brake control consisting of a brake band 53 which encircles a brake surface at the uppermost portion of the traction frame casting 54. The said brake band 53 has one end dead-ended or attached to an arm 55 on the base casting 24 of the body

A. The other end of the brake band, its live end, is connected with one arm of a bell crank lever 56 also mounted on said base casting 24. This bell crank lever 56 is operable by a foot piece or tread member 57 that when depressed, will apply the brake band to the brake surface of the casting 54, and in this way as the crane body A is swung under the influence of traveling action of the gear 42 around the gear 43, said body may be stopped at any suitable point in its movement by mere depression of the foot piece 57 by the operator.

It is notable in regard to the traction frame casting 54 that it is somewhat peculiarly constructed in that a central body portion is equipped with integral offstanding arms 58 and these arms are formed with the longitudinal traction belt supporting frames 59 integral therewith. The traction belts 48 may be mounted upon the frames 59 in quite the usual manner but the unique feature of construction that I refer to is the employment of a single traction base frame having a central body portion and integral traction belt frames at its opposite sides, the whole a single unit. The arms 58 may be provided with openings for passage of the sprocket driving chains 51, as seen best in Figure 1.

It is noted that the operating means for the combined clutch and brake sets 49 as has heretofore been proposed includes certain control rods and parts including rods or shafts leading down through the hollow center pin shaft 44, same not being illustrated in detail in this application in view of the fact that the traction driving means and the control of the lower crane machinery therein constitutes an invention separate from the one embodied in this case.

A noteworthy feature lies in the instrumentalities for operating the brakes, that is, the steering brakes which are availed of for the traction lock as well as the steering means, thereby eliminating parts and complexity of construction. Pivotaly mounted between their ends of the turntable of the crane are two control levers 60 and 61. Extending down through the center pin on the axis of rotation are two tubular members 62 and 63 which are arranged concentrically one within the other, the ends of these tubular members being affixed to the levers 60 and 61 which are mounted so that operation thereof causes upward or downward movement of the tubes 62 and 63. The lever 61 has an operative connection with the swing brake so that operation thereof causes operation of the latter. Through the pipe 63 and bell crank 64 the operating member 61 is operatively connected with the steering brakes in the following manner. The shaft 65 is included in the traction construction of the machine and keyed thereto is a yoke 66 which is designed for shifting the jaw clutch. A crank 67 is

splined to the other end of the shaft 65 and is connected with the instrumentalities associated with the operating lever 60 through the medium of the link shown at 68. The bell 5 crank 69 is pivotally mounted on the shaft 65 and has a finger for operating the brake 49, the other arm of the bell crank abutting against the side of the arm 67 to which the link 68 is connected. This abutting relationship allows the bell crank 69 to rotate counter-clockwise without entailing rotation of the shaft 65 when motion is imparted from the lever 61, but when the lever 60 is operated, parts 69, 67, and 66 must move as a 10 unit. A spring 70 is included in the construction which constantly tends to hold the bell crank 69 in its abutted relation with respect to the crank 67. The remainder of the 15 brake construction together with its operating instrumentalities is of the well known type, the operation of which will be apparent from the drawings. In operating the crane if the lever 60 is lifted the clutch at the left side of the machine will be released and the brake set, while if this lever is depressed beyond its natural position, the clutch on the right side will be released and the brake set. However, upon operation of the lever 61 in an 20 upward direction, the swing brake will be applied throwing the machine into tractive operation. Depression of the lever 61 causes a release of the swing brake and a setting of 25 both of the steering brakes.

General résumé of construction and operation

The drum 12 is the dipper hoist drum operating the cable 2. The drum 11 is the crowding out and racking in means operating the cable 1 in conjunction with the crowding and 30 racking pinion 1^a on the boom. The main worm gear at 16 is driven from the worm shaft 5 by the worm 17 to thereby turn the shaft 10 and operate either one of the drums 11 and 12 or both of them, dependent upon 35 the clutching of these drums to the shaft 10. In this way, the drum 11 may be turned in one direction as for crowding out the dipper E. To turn it in the opposite direction for racking in the dipper, the drum 11 may be 40 reversely operated by the drive from the worm shaft 5, worm 17, worm gear 18, spur gears 31 and 32, shaft 33, spur gears 35 and 36, the latter affixed to the drum 11 in some 45 substantial way.

For operating the boom hoist drum 37, the drive is taken from the worm 17, worm gear 18, spur gears 31 and 32, shaft 33, boom hoist clutch 33^a and gear 35, the latter adjusted so as to enter the toothed gear recess 50 in the left end of the drum 37.

For swinging the body A of the crane in either direction, one of the clutch means 51^a and 52^a is availed of to connect the shaft 20 to rotate a certain one of the bevel pinions 55 or gears 39 and 40. The operative pinion

turns the cupped gear 28, its connected gear 42, and the gear 42 travels around the umbrella gear 43 which has previously been locked from movement by locking the traction shaft 47 through the application of both 70 brakes of the brake and clutch sets 49.

Stoppage of the swinging of the body A is effected by the brake band 53 operated by the foot piece 57, or by reverse clutch.

To transmit driving operation to the traction devices 48, the brake band 53 may be used to hold the body A stationary in respect to the traction base. The drive may then be taken off through the clutch devices 51^a and 52^a operating the cupped gear 28 and its pinion 42 in either of opposite directions, for forward driving of the traction members 48 or rearward driving as required. Turning of the swing and traction gear 42 will rotate the umbrella gear 43, turn the center pin shaft 44 and transmit motion to the traction shaft 47 through the gears 45 and 46. The motion of the shaft 47 may be transmitted to either or both of the traction members 48 by the combined clutch and brake sets 49.

Having thus described my invention, what I claim as new and desire to secure by Letters Patent of the United States, is:—

1. In a crane, in combination, a base, a crane body thereon, excavating means carried by the crane body, and operating machinery on the crane body for the excavating means, comprising an engine on the body, a worm shaft and worm being directly connected to said engine, drum mechanism for the excavating means, and driving connections between the worm aforesaid and said drum mechanism.

2. In a crane, in combination, a base, a crane body thereon, excavating means carried by the crane body, and operating machinery on the crane body for the excavating means, comprising an engine on the body, a worm shaft and worm driven from said engine, drum mechanism for the excavating means, and driving connections between the worm aforesaid and said drum mechanism, a housing for the worm and worm shaft and rigidly mounted on the crane body, a worm gear operable from said worm and arranged in said housing, and operating drums for the drum mechanism and mounted on said housing and arranged to be driven by said worm gear.

3. In a crane, in combination, a base, a crane body thereon, excavating means carried by the crane body, and operating machinery on the crane body for the excavating means, comprising an engine on the body, a worm shaft and worm driven from said engine, drum mechanism for the excavating means, and driving connections between the worm aforesaid and said drum mechanism, a housing for the worm and worm shaft rigidly mounted on the crane body, a worm gear op- 120 125 130 135 140 145 150 155 160 165 170 175 180

erable from said worm and arranged in said housing, and operating drums for the drum mechanism and mounted on said housing and arranged to be driven by said worm gear, the 5 said drums being disposed at opposite sides of the housing for the reception of cable means and supported by the housing.

4. In a crane, in combination, a base, a crane body thereon, excavating means carried 10 by the crane body, and operating machinery on the crane body for the excavating means, comprising an engine on the body, a worm shaft and worm driven from said engine, drum mechanism for the excavating 15 means, and driving connections between the worm aforesaid and said drum mechanism, a housing for the worm and worm shaft rigidly mounted on the crane body, a worm gear operable from said worm and arranged in 20 said housing, and operating drums for the drum mechanism and mounted on said housing and arranged to be driven by said worm gear, the said drums being disposed at opposite sides of the housing for the reception of 25 cable means and supported by the housing, a shaft with which the said worm gear is connected, and clutch means for clutching said shaft to each one of the drums for driving said drums in one direction.

5. In a crane, in combination, a base, a crane body thereon, excavating means carried by the crane body, and operating machinery on the crane body for the excavating means, comprising an engine on the body, a worm 35 shaft and worm driven from said engine, drum mechanism for the excavating means, and driving connections between the worm aforesaid and said drum mechanism, a housing for the worm and worm shaft rigidly 40 mounted on the crane body, a worm gear operable from said worm and arranged in said housing, and operating drums for the drum mechanism and mounted on said housing and arranged to be driven by said worm 45 gear, the said drums being disposed at opposite sides of the housing for the reception of cable means and supported by the housing, a shaft with which the said worm gear is connected, and clutch means for clutching said 50 shaft to each one of the drums for driving said drums in one direction, and means operable from the worm shaft for actuating one of the said drums in a direction reverse to that previously referred to.

6. In a crane of the class described, a crane body having operating mechanism for excavating machinery comprising an engine disposed with its driving shaft lengthwise of the body, driving means comprising a housing 55 for worm gearing disposed on said body, a worm shaft drivably connected to said engine and entering said housing and having a worm thereon, a main worm gear operable from said worm and mounted in the housing, 60 cable drums for operating an excavating de-

vice and mounted on said housing, means actuated by said worm gear to turn said drums in one direction, and secondary gearing driven by said worm for turning one of said cable drums in a reverse direction.

7. In a crane of the class described, a crane body having operating mechanism for excavating machinery comprising an engine disposed with its driving shaft lengthwise of the body, driving means comprising a 75 housing for worm gearing disposed on said body, a worm shaft drivably connected to said engine and entering said housing and having a worm thereon, a main worm gear operable from said worm and mounted in the housing, 80 cable drums for operating an excavating device and mounted on said housing, means actuated by said worm gear to turn said drums in one direction, and secondary gearing driven by said worm for turning one of said cable 85 drums in a reverse direction, a base for the crane body and traction means therefor, and driving connections between the secondary gearing and said traction means.

8. In a crane of the class described, a crane 90 body having operating mechanism for excavating machinery comprising an engine disposed with its driving shaft lengthwise of the body, driving means comprising a housing for worm gearing disposed on said body, a 95 worm shaft drivably connected to said engine and entering said housing and having a worm thereon, a main worm gear operable from said worm and mounted in the housing, 100 cable drums for operating an excavating device and mounted on said housing, means actuated by said worm gear to turn said drums in one direction, and secondary gearing driven by said worm for turning one of said cable 105 drums in a reverse direction, a base for the crane body and traction means therefor, and driving connections between the secondary gearing and said traction means, including a swing and traction gear, a driving gear attached to the swing and traction gear, and 110 means for communicating reverse movements to said driving gear from said secondary gearing.

9. In a crane, in combination, a base, a body mounted thereon, an excavating device carried by the body and operating means for the excavating device including an engine disposed longitudinally of the body at the central portion thereof, a shaft and worm drivably connected to said engine, a worm 115 gear unit comprising a housing at the central portion of the body in alignment with the engine and receiving said shaft and worm, a worm gear operable from said worm, and drum mechanism in operative connection 120 with said worm gear.

10. In a crane, in combination, a base, a body mounted thereon, an excavating device carried by the body and operating means for the excavating device including an engine 125

disposed longitudinally of the body at the central portion thereof, a shaft and worm drivably connected to said engine, a worm gear unit comprising a housing at the central portion of the body in alignment with the engine and receiving said shaft and worm, a worm gear operable from said worm, and drum mechanism in operative connection with said worm gear, and including spaced 5 separate drums independently rotatable upon the said housing at opposite sides thereof, and cable means received by said drums and connected with the excavating device aforesaid. 10

body mounted thereon, an excavating device carried by the body and operating means for the excavating device, including an engine disposed longitudinally of the body at the central portion thereof, a shaft and worm drivably connected to said engine, a worm gear unit comprising a housing at the central portion of the body in alignment with the engine and receiving said shaft and worm, a main worm gear operable from said worm, and drum mechanism in operative connection with said worm gear, and including spaced 70 75 separate drums independently rotatable upon the said housing at opposite sides thereof

11. In a crane, in combination, a base, a body mounted thereon, an excavating device carried by the body and operating means for the excavating device, including an engine disposed longitudinally of the body at the central portion thereof, a shaft and worm drivably connected to said engine, a worm gear unit comprising a housing at the central portion of the body in alignment with the engine and receiving said shaft and worm, a main worm gear operable from said worm, and drum mechanism in operative connection with said worm gear, and including spaced separate drums independently rotatable, upon the said housing at opposite sides thereof, cable means received by said drums and connected with the excavating device aforesaid, means to operatively connect said drums to the main worm gear aforesaid to turn the drums in one direction, and secondary gearing operable from the worm shaft for turning one of said drums in an opposite direction, and a swing and traction gear operably connected with the secondary gearing aforesaid.

40 12. In a crane, in combination, a base, a body mounted thereon, an excavating device carried by the body and operating means for the excavating device, including an engine disposed longitudinally of the body at the central portion thereof, a shaft and worm drivably connected to said engine, a worm gear unit comprising a housing at the central portion of the body in alignment with the engine and receiving said shaft and worm, a main worm gear operable from said worm, and drum mechanism in operative connection with said worm gear, and including spaced 45 separate drums independently rotatable upon the said housing at opposite sides thereof, cable means received by said drums and connected with the excavating device aforesaid, means to operatively connect said drums to the main worm gear aforesaid to turn the drums in one direction, and secondary gearing operable from the worm shaft 50 for turning one of said drums in an opposite direction, said secondary gearing including a secondary worm gear in alignment with the main worm gear and the worm shaft, and a train of gears intermediate the secondary worm gear and the reversible one of the drums aforesaid, a swing and traction gear adjacent to the secondary gearing aforesaid, and means for communicating reverse movements to said swing and traction gear from the secondary 55 gearing. 110 115 120 125

55 13. In a crane, in combination, a base, a body mounted thereon, an excavating device carried by the body and operating means for the excavating device, including an engine disposed longitudinally of the body at the central portion thereof, a shaft and worm drivably connected to said engine, a worm gear unit comprising a housing at the central portion of the body in alignment with the engine and receiving said shaft and worm, a main worm gear operable from said worm, and drum mechanism in operative connection with said worm gear, and including spaced 60 separate drums independently rotatable upon the said housing at opposite sides thereof, cable means received by said drums and connected with the excavating device aforesaid, means to operatively connect said drums to the main worm gear aforesaid to turn the drums in one direction, and secondary gearing operable from the worm shaft for turning one of said drums in an opposite direction, said secondary gearing including a secondary worm gear in alignment with the main worm gear and the worm shaft, and a train of gears intermediate the secondary worm gear and the reversible one of the drums aforesaid. 65 130

65 13. In a crane, in combination, a base, a

65 13. In a crane, in combination, a base, a portion of the body in alignment with the 139

engine and receiving said shaft and worm, a main worm gear operable from said worm, and drum mechanism in operative connection with said worm gear, and including spaced 5 separate drums independently rotatable upon the said housing at opposite sides thereof, cable means received by said drums and connected with the excavating device aforesaid, means to operatively connect said drums to 10 the main worm gear aforesaid to turn the drums in one direction, and secondary gearing operable from the worm shaft for turning one of said drums in an opposite direction, said secondary gearing including 15 a secondary worm gear mounted on a shaft and in alignment with the main worm gear and the worm shaft and operable from said worm, and a train of gears intermediate the secondary worm gear and the 20 reversible one of the drums aforesaid, a swing and traction gear adjacent to the secondary gearing aforesaid, and means for communicating reverse movements to said swing and traction gear from the secondary gearing; 25 said means including separate gears, separate gears carried by the secondary worm gear shaft and independently connectable therewith, and a driving gear intermediate and operatively connected to said separate gears 30 last mentioned, and the swing and traction gear for transmitting driving action to the latter.

16. In a crane, in combination, a crane body, an engine thereon, a worm gear driving unit connected with the engine, an excavating device carried by the body for operation from said driving unit, the driving unit comprising a worm gear housing, cable drums rotatably mounted thereon, a driving 35 worm shaft connected with the engine, and entering the housing, a worm gear operable from said worm shaft, means for connecting the worm gear with the said drums at will, and means for supporting the drums upon 40 the worm gear housing so that the latter forms the sole means of support therefor.

17. In a crane, in combination, a crane body, an engine thereon, a worm gear driving unit connected with the engine, an excavating device carried by the body for operating from said driving unit, the driving unit comprising a worm gear housing, cable drums rotatably mounted thereon, a driving worm shaft connected with the engine, and entering the housing, a worm gear operable 50 from said worm shaft, means for connecting the worm gear with the said drums at will, and means for supporting the drums upon the worm gear housing so that the latter forms the sole means of support therefor, said crane body having a base, the worm gear housing being provided with off-standing arms anchored to the base of the crane body so as to be rigidly supported thereby, a driving device supported by said base, and trac- 55

tion means for said body and operable from said driving device.

18. In a crane, in combination, a crane body, an engine thereon, a worm gear driving unit connected with the engine, an excavating device carried by the body for operating from said driving unit, the driving unit comprising a worm gear housing, cable drums rotatably mounted thereon, a driving worm shaft connected with the engine, and entering the housing, a worm gear operable from said worm shaft, means for connecting the worm gear with the said drums at will, and means for supporting the drums upon the worm gear housing so that the latter forms the sole means of support therefor, said crane body having a base, the worm gear housing being provided with off-standing arms anchored to the base of the crane body so as to be rigidly supported thereby, a driving device supported by said base, and traction means for said body and operable from said driving device. 70 75 80 85

19. In a crane, in combination, a crane body, an engine thereon, a worm gear driving unit connected with the engine, an excavating device carried by the body for operating from said driving unit, the driving unit comprising a worm gear housing, cable drums rotatably mounted thereon, a driving worm shaft connected with the engine, and entering the housing, a main worm gear operable from said worm shaft, means for connecting the worm gear with the said drums at will, and means for supporting the drums upon the worm gear housing so that the latter forms the sole means of support therefor, said crane body having a base, the worm gear housing being provided with off-standing arms anchored to the base of the crane body so as to be rigidly supported thereby, a driving device, and traction means for said body and operable from said driving device, secondary driving gearing comprising a gear in the housing and operable from said worm shaft, and a shaft carried by said housing and connected with the last named gear, and a train of gearing running from the last mentioned shaft to one of the drums previously referred to for driving the said drum in a direction reverse to that in which it may be driven from the main worm gear. 90 95 100 105 110 115

20. In a crane, the combination of a crane body, an excavating device thereon, and an operating unit on the body including an engine, and a worm gear housing, for the operation of the excavating devices, said unit also including the gear 16, and the drums 11 and 12 operable from said gear 16 substantially as set forth, together with the shaft 10 for connecting the gear 16 with the drums 11 and 12, the shaft 5 for driving the gear 16, the worm 17 on the shaft 5 and engaging the gear 16, and secondary gearing operable from the shaft 5 and arranged to drive the 120 125 130

drum 11 in a direction reverse to that in which the drum 11 will be driven directly from the shaft 5.

21. In a crane, operating machinery as described including the worm gear housing 7, the anchorage means 7^a, 7^b for said housing arranged at the base thereof, the independently rotatable drums 11 and 12 mounted upon the housing, the worm gears 16 and 18, the worm shaft drive means therefor including the parts 17 and 5, means for driving the drums 11 and 12 from the gear 16, and other means for driving the drum 11 from the worm gear 18 in a direction opposite to that in which it is driven by the worm gear 16.

15 In testimony whereof I affix my signature.

ERICH H. LICHTENBERG.
